KITE REEL

Henry Allen Wilson, 1000 Eldorado Ave.,
Clearwater Beach, Fla.

Filed Oct. 23, 1962, Ser. No. 72,235

Term of patent 14 years

(Cl. D41—1)

FIG. 1

FIG. 2

FIG. 3

FIG. 4

FIG. 1 is an axonometric view of the kite reel;
FIG. 2 is a rear elevation thereof;
FIG. 3 is a front elevation thereof, and
FIG. 4 is a vertical section on the line 4—4 of FIG. 3.
I claim:
The ornamental design for a hand kite reel, substantial-
ly as shown.
